(57) CLAIM

The ornamental design for a tape measure holder, as shown and described.

DESCRIPTION

FIG. 1 is a front perspective view of a tape measure holder, showing my new design;

FIG. 2 is front view thereof;

FIG. 3 is a rear view thereof;

FIG. 4 is a left side view with a right side view being the mirror image thereof;

FIG. 5 is a top view thereof; and,

FIG. 6 is a bottom view thereof.

The broken lines are for illustrative purposes only and form no part of the claimed design.
